METHOD OF AND MACHINE FOR
ASSEMBLING SHOE PARTS

Robert H. Lawson, Beverly, Mass., assignor to
United Shoe Machinery Corporation, Paterson,
N. J., a corporation of New Jersey

Application January 20, 1933, Serial No. 652,701
Renewed December 26, 1935

111 Claims. (Cl. 12—4)

The present invention relates to the manufacture of shoes and is illustrated as embodied in a machine for assembling and shaping shoe parts upon a last.

In the commercial manufacture of most types of shoes the shoe parts, which usually comprise an upper having a lining stitched thereto and a heel stiffener or counter inserted between the upper and lining at their heel ends, are assembled upon a last and are next operated upon by a pulling-over machine to stretch the upper lengthwise of the last, and also to impart to the toe end of the upper the general shape of the toe end of the last. Unless the front ends or wings of the counter are held in position heightwise of the last during the pulling-over operation there is a tendency for the wings of the counter to sag downwardly. This condition must be corrected before the heel seat lasting operation. The correction of this condition is made particularly difficult by the fact that adhesive has been applied to unite the counter, upper and lining together, and if the adhesive has set with the counter misplaced, it is sometimes necessary to break the bond between the counter and the other shoe parts before the counter can be pulled up into proper position heightwise of the last.

It is an object of the present invention to hold the wings of the counter in their proper position heightwise of the last during the pulling over operation while the upper is drawn forwardly of the last, and accordingly, the invention, in one aspect, comprises a method of assembling and shaping shoe parts upon a last which consists in holding the extremity of the upper at the heel end of the shoe from movement heightwise of the last, tensioning the shoe parts heightwise of the last at opposite sides of its heel portion, holding the parts so tensioned, and thereafter drawing the upper forwardly of the last, for example in a pulling-over machine, while the shoe parts are so held.

As a further aspect of the invention, the shoe parts are held tensioned heightwise thereof at opposite sides of their heel portions by means engaging the margins of the shoe parts at opposite sides of their heel portions while permitting movement of the upper lengthwise of the last in order that the upper, at its heel end, may be drawn forwardly of the last while such tension is maintained.

In the illustrated machine, and in accordance with a feature of the invention, the wings of the counter are held in position under heightwise tension by self-locking grippers carried by a work support which is portable with the last and shoe

parts. The grippers which engage the margin of the shoe parts, as illustrated in the drawings, are so constructed that a strain on the counter or the upper tending to withdraw the shoe parts from the grippers urges their gripping surfaces toward each other, thereby increasing the gripping action. In order to cooperate with the grippers to tension the shoe parts heightwise thereof there is provided in the portable work supporting member, in accordance with a further feature of the invention, means, for example, a presser arm, for pressing against the last bottom forwardly of the grippers.

It is of great importance to the proper performance of the heel seat lasting operation and also to the appearance of the finished shoe that the counter, if it be a flanged counter, be assembled with its flange held firmly against the margin of the heel seat and with its rear end substantially adjacent to the rear end face of the last. It is an object of the present invention to position the counter properly upon the last and to secure the counter in such position. Accordingly, the invention, in another of its aspects, comprises a method of assembling and shaping a shoe upper, a flanged counter, and a lining upon a last which comprises holding the work by the lasting allowance at the heel end thereof, inserting a last into the work, urging the last rearwardly thereof, and pressing the last heightwise thereof against the flange of the counter while the counter is held against movement heightwise of the last. Accordingly, for practicing this method, and as a further feature of the invention there is provided means for holding the upper by its lasting allowance, means for pressing the last into the upper and means for urging said last rearwardly and upwardly. The upward movement of the last is arrested by a stop arranged to oppose the pressure of the last against the flange of the counter. The rearward movement of the last is arrested by means, for example, a back stop, arranged to be engaged by the portion of the heel end of the upper that is adjacent to the heel seat in order to cause the counter to conform to the heightwise curvature of the rear end face of the last.

The arrangement of the shoe parts upon the last so that the heel end of the upper is properly positioned with respect to the rear end face of the last is a matter which is usually left to the skill of the assembling machine operator. It is an object of the present invention to provide means for properly locating the heel end of the upper with respect to its last and, accordingly, a feature of the invention contemplates the pro-

vision in a machine for assembling an upper upon its last, of an upper supporting member arranged to engage the lasting allowance of the upper at its heel end, and means constructed and arranged to engage the upper in the crease of the back seam in order to locate the back seam in a vertical plane extending lengthwise of the upper.

The upper as it comes to the assembling machine is often distorted at its heel end making it desirable to rearrange the upper, and accordingly, a further feature of the invention contemplates the provision in a machine for assembling a shoe upper upon its last, of supporting means constructed and arranged to engage the lasting allowance of the heel end of the upper, and means for tensioning the heel end of the upper heightwise thereof to straighten it.

These and other features of the invention will appear more fully from the following detailed description taken in connection with the accompanying drawings and will be pointed out in the appended claims.

In the drawings,

25 Fig. 1 is a side elevation of the upper portion of a machine embodying the features of the present invention showing the parts in their initial position with an upper in position to be operated upon, the lower portion of the machine 30 being broken away;

35 Fig. 2 is a side elevation showing the position of the parts after the completion of the operation upon the shoe but before the last with the shoe parts assembled thereon has been released for removal from the machine, parts of the shoe and of the column being broken away;

40 Fig. 3 is a view similar to Fig. 1 showing the position of the parts after the last has been released;

45 Fig. 4 is a detail view in front elevation of the head of the machine with the work support removed therefrom;

Fig. 5 is a perspective view showing the heel end of a last with the shoe parts held thereto by 45 the portable work support;

Fig. 6 is a detail, partly in section, illustrating one of the self locking grippers;

50 Fig. 7 is a detail view in side elevation and partly in section of certain parts in the head of the machine showing their position with relation to the heel end of the upper just before the operator steps on the treadle;

55 Fig. 8 is a side elevation similar to Fig. 7 illustrating the insertion of a last into the shoe parts;

Fig. 9 is a detail perspective view illustrating the gripper for the heel end of the upper, and parts associated therewith;

Fig. 10 is a detail view of certain parts of the 60 gripper assembly shown on Fig. 9;

Fig. 11 is a detail perspective view illustrating the gripper shown in Fig. 9 in connection with parts of its actuating mechanism;

Fig. 12 is a sectional detail view taken substantially on the line 12-12 of Fig. 2;

Fig. 13 is a fragmentary detail view of the tack driving mechanism;

Fig. 14 is a sectional view taken substantially on the line 14-14 of Fig. 13;

70 Fig. 15 is a perspective detail view illustrating parts of the tack driving mechanism;

Fig. 16 is a sectional view taken substantially on the line 16-16 of Fig. 2; and

75 Fig. 17 is a fragmentary detail view illustrating certain parts in the head of the machine in their

position prior to the depression of the treadle.

Referring to Fig. 1, the invention is embodied in a machine comprising a column 20 and a machine head 22 secured to the top of the column and extending upwardly and then forwardly 5 therefrom. At its forward end the machine head 22 curves downwardly and is slightly offset from its rearward portion, as shown in Fig. 4. In the under surface of said offset portion there is provided a horizontal T-way 24 arranged longitudinally of the machine head for the reception of a work support 26 (Figs. 1 and 5) provided with a slide which is T-shaped in cross section to permit it to be supported within the T-way 24. At its forward end the work support is provided with arms 28 extending laterally therefrom in opposite directions. At the outer end of each of the arms 28 there is pivoted a work engaging gripper 30. The arms 28 are preferably so located lengthwise of the upper that the grippers 20 30 engage the upper, counter, and lining at the forward ends or wings of the counter.

As illustrated in Fig. 6, each of the grippers 30 comprises a U-shaped member arranged with its open end downward and a swinging gripper arm 38 pivoted to said member. The arm 32 of the gripper member has teeth 34 formed in its inner surface and arranged to prevent the withdrawal of the work from the grippers while permitting the work to be freely inserted between 30 the gripper jaws. The outer arm 36 of the U-shaped gripper member is somewhat longer than the inner arm 32 and is bifurcated at its lower end for the reception of a swinging gripper arm 38 which is pivoted thereto at 40. The gripper arm 38 is yieldingly held in operative position, by a torsion spring 42 retained within the bifurcated end of the arm 36, the operative position of the gripper arm 38 being determined by a stop pin 44 mounted in the bifurcated end of 40 the arm 36. The gripper arm 38 extends inwardly with an upward inclination from its pivot 40 and is provided at its inner end with gripping teeth which are constructed to prevent the withdrawal of the work from the gripper while permitting the work to be freely inserted therein. If desired the under surface 46 of the horizontal portion of the U-shaped gripper member may serve as a gage for determining the position of the shoe parts relatively to the work support. 50 The location of the pivot 40 relatively to the gripping surface of the inner arm 32 is such that an upward movement of the shoe parts between the gripper jaws causes the arm 38 to swing about its pivot in a direction such that its gripping surface travels away from the gripping surface of the arm 32 and thus permits the lasting allowance of the shoe parts to pass upwardly between the gripping jaws with no substantial interference. Conversely it will be seen that a 55 strain on the shoe parts, after they have been positioned between the gripper jaws, tending to withdraw the parts therefrom causes the gripper arm 38 to swing about its pivot 40 in a direction such that its gripping surface is urged toward the gripping surface of the arm 32, thereby increasing the force of the gripping action. As best shown in Fig. 5, the gripping teeth extend lengthwise of the upper and are coextensive with the width of the grippers, thus permitting the upper parts to move lengthwise thereof when the grippers are in operative position. The gripper arm 38 is extended outwardly thereof to form a tail piece 48 which may be readily manipulated to release the work from the grippers. It 75

is unnecessary to manipulate the arm 38 when the work is inserted into the grippers as the introduction of the work between the gripper jaws causes the gripper arm 38 to swing sufficiently 5 to admit the work.

The shoe parts comprising the counter 61, upper 59 and lining 63, are supported at their rearward ends upon an upwardly curved pin 50 arranged to extend through openings formed in 10 the margins of said shoe parts. The alignment of said openings, in order to permit the insertion of the pin 50 therethrough, serves to bring the parts into the proper relation to each other at that point. In order to accommodate the pin 50 15 and at the same time to permit the greater portion of the flange of the counter to lie flat against an insole 168, the openings in the counter and the lining for the reception of the pin 50 are formed in tabs 52 and 54 (Fig. 5) formed in the 20 lasting allowance of the counter and lining, respectively, and bent into perpendicular relation to the heel seat face of the insole. In order further to promote the flattening of the flange of the counter against the margin of the insole 25 the flange of the counter is slashed at points rearward of the grippers 30, as indicated at 65 in Fig. 5. The curved pin 50 is mounted in a combined heel seat plate and presser arm 56 pivoted to a downward extension 58 of the rearward end of the work support 26, said pin extending rearwardly with an upward curvature from the edge face at the rearward end of the heel seat plate.

In assembling the upper, counter, and lining upon the work support the operator brings the openings at the rearward ends of the parts into alignment and passes the hook 50 therethrough, the work support at that time having been removed from the machine. With the parts thus supported upon the pin 50 the operator slides the work support into the T-way 24 in the machine head (Fig. 1) and moves the work support rearwardly of the machine until it arrives at the position indicated by Fig. 7. In this position 45 the work support 26 is held from return movement by a latch pin 60 which engages within a socket 62 provided at the upper surface of the work support 26 (Fig. 5). The latch pin 60 is slidably mounted in a vertical bore in the offset portion of the machine head (Fig. 4) and is 50 yieldingly actuated by a bell crank lever 64 (Fig. 1) pivoted to the upper end of a lug 67 extending rearwardly and upwardly from the offset portion of the machine head. At its forward end the horizontal arm of the bell crank lever 64 is constructed and arranged to engage within a slot 66 (Fig. 4) provided in the upper end of the latch pin 60. A spring 68 is connected at one end to the vertical arm of the bell crank lever 64 and at its opposite end to the machine head whereby the bell crank lever, as seen in Fig. 1, is urged counterclockwise, said movement being limited by an adjustable abutment screw 70 projecting upwardly from the machine head. 55 The latch pin 60 is lifted to permit the work support to travel rearwardly in the T-way 24 by the engagement of a cam surface 72 formed at the rearward end of the work support 26 with a corresponding cam surface 74 formed in the forward face of the latch pin at its lower end.

The rearward movement of the work support 26 operates, through connections to be described, to close a gripper upon the back of the shoe parts. Said gripper consists of a blade-like member 76 (Figs. 1 and 9) constructed and arranged to en-

gage the back of the upper within the crease formed at the back seam and a plate-like member 80 constructed and arranged to engage the inner surface of the shoe parts and provided with a convex gripping surface in order to accommodate it to the curvature of the heel end of the last and upper. Preferably the gripper plate 80 is as thin as practicable in order that it may cause no substantial separation of the last and shoe parts (Fig. 2). As shown in Fig. 9 the gripper blade 76 is provided with a downwardly extending shank 82 and a hub 84; and the gripper plate 80, as shown in Fig. 9, is provided with an arm 86 extending upwardly therefrom with a rearward inclination, and at its opposite side 15 the gripper plate is provided with an upstanding lug 88. The gripper blade 76 and an arm 90 are arranged between the lug 88 and the arm 86 of the gripper plate and are pivoted coaxially thereto. The gripper plate 80 is held in its open 20 position, as shown in Fig. 9, by a compression spring 100 mounted in a hollow link 92 pivoted to the rearward end of the arm 90. At its forward end the link is provided with a slot 94 which receives a headed pin 96 secured to the end of the 25 arm 86 (Fig. 11). The pin 96 is yieldingly held at the forward extremity of the slot 94 by a plunger 98 arranged to slide in a longitudinal bore formed in the link 92 and backed up by the compression spring 100. In its open position 30 the gripper assembly is supported upon a stud 102 projecting laterally from the machine frame and arranged to be engaged by a hook 104 pivoted to the arm 90 (Fig. 10). The gripper blade 76 is supported in its upstanding position 35 (Fig. 9) by a toothed segment 106 pivoted to the arm 90 and arranged to engage the under surface of a tail piece 108 extending rearwardly from the gripper blade 76. The segment 106 is held in its gripper supporting position by a lever 110 40 pivoted to the arm 90 and provided at its forward end with teeth constructed and arranged to mesh with the teeth formed in the segment 106. The gripper blade 76 is released from its gripping position by actuating the lever 110, as 45 hereinafter described, to swing the segment 106 clockwise, as seen in Fig. 9. The gripper plate 80 is brought into gripping position by the rearward movement of the work support 26 to bring the upper into position to be operated upon. As 50 illustrated, the connections between the work support and the gripper mechanism for actuating the gripper plate comprise a horizontal rod 112 (Fig. 2) slidably mounted in a bore provided in a lateral extension 114 of the machine head 55 (Fig. 4). At its rearward end the rod 112 engages a rocker arm 116 pivoted to the machine head and provided at its lower end with a stud 118 (Fig. 11) arranged to engage the rear edge face of an arm 120 projecting upwardly from the rearward end of the link 92. The engagement of the stud 118 with the arm 120 causes the link 92 to swing counter-clockwise, as seen in Fig. 11. In the course of the swinging movement of the link 92 a cross pin 122 carried thereby engages a 60 tail 124 formed in the hook 104, swinging the hook in a clockwise direction, as seen in Fig. 10, and disengaging it from its supporting stud 102. As the hook 104 is disengaged from its supporting stud 102 the link 92 has swung slightly beyond a position of alignment with the arm 86 65 and the compression spring 100 has begun to operate upon the arm 86 to swing the gripper plate 80 into gripping position. After the hook 104 has disengaged the supporting stud 102 the 70 75

forward end of the gripper assembly is left unsupported but the action of the compression spring 100 to bring the gripper plate 86 into gripping position is more rapid than the action of gravity upon the gripper assembly and, consequently, as the link 92 swings downwardly, the gripper is brought into engagement with the back of the upper, as shown in Fig. 2. The gripper is now free to move heightwise of the last in order to tension the rear ends of the upper and lining heightwise thereof. At its rearward end the gripper assembly is pivoted to the lower end of a link 128 the upper end of which is pivoted to the machine frame (Fig. 2). It will thus be seen that the gripper assembly is free to move lengthwise of the last. The pressure of the gripper upon the work is light enough to obviate any substantial penetration or marking of the upper by the edge of the gripper blade 76, and the edge of said blade is sufficiently blunt to permit the shoe parts to move laterally thereof between the gripper members in order that the edge of the gripper blade may be caused to engage within the crease at the back seam of the upper. The upper per 59, as illustrated in the drawings, is provided at the back of its heel end with a cap piece 127 (Fig. 1) which is stitched to the back of the upper near its edge and covers a portion of the back seam. The edge of the cap piece 127 provides an abutment for the gripper blade 76 preventing the gripper 76, 80 from sliding off the back of the upper as it is depressed to tension the heel end of the upper heightwise thereof.

After the work support has been moved rearwardly of the machine within its T-way 24, and the latch pin 60 has engaged within the socket 62 in order to hold the work support from return movement, the operator adjusts the heel end of the shoe parts until the gripper blade 76 engages within the crease at the back seam of the upper. The operator then passes the margin of the shoe parts at opposite sides of the heel end thereof upwardly between the jaws of the grippers 30.

The operator now grasps the last 78 by its toe end and inserts it into the upper at an inclination thereto (Fig. 8), then swings the rear end of the last upwardly within the upper in order to wipe the rear end face of the last against the rear end of the lining to rub out any wrinkles that may have been formed by the insertion of the counter 61 between the upper and lining.

The operator now depresses a treadle in order successively to wind up a tack driving spring 218, to depress the gripper 76, 80, and to depress the last forwardly of the grippers 30 in order to tension the upper heightwise thereof. Simultaneously with the above operations the depression of the treadle operates, through mechanism to be described, to press the last rearwardly and upwardly of the shoe parts. At the conclusion of the aforesaid operations a further depression of the treadle operates to drive a tack through the back of the shoe parts and into the last at one side of the back seam and then to release the gripper 76, 80, to retract the last pressing means and to eject the work support 26 from its operative position. The retraction of the treadle operates to reset the parts for the repetition of the cycle of operations above described.

Referring now more particularly to the actuation of the gripper 76, 80 to tension the rear end of the shoe parts heightwise thereof, the cross pin 122 in the hollow link 92 (Fig. 11), has pivoted thereto the lower end of a link 128. The link 128 is surrounded by a compression spring 130

(Fig. 2) the upper end of which supports a block 132 which is slidably mounted upon the link 128. The block 132 is moved downwardly upon the link 128, in order to compress the spring 130, by a bell crank lever 134 pivoted to the machine frame and pivoted at the forward end of its horizontal arm to the block 132. A pin 136 projects laterally from the upper end of the vertical arm of the bell crank lever 134 and is received within a dove-tailed notch 138 in the under surface of an arm 140 after said arm has advanced from its initial position, as shown in Fig. 17, to a position in which the notch 138 registers with the pin 136. During this interval the torsion spring 218, which actuates a tack driver 186 (Fig. 1), is being wound up by mechanism hereinafter described. The arm 140 is pivoted to a bell crank lever 142 which in turn is pivoted to the upper end of a plate 144 secured to a lateral extension 146 of the machine head (Fig. 12). A link 148 connects the bell crank lever 142 to an arm 150 pivoted to a rearward extension of the machine head, and a link 152 connects the arm 150 to a rocker arm 154 pivoted at 156 to the machine column. A link 158 (Fig. 1) connects the rearward end of the rocker arm 154 to the treadle 160. It will thus be seen that the depression of the treadle moves the arm 140 forwardly from its position in Fig. 17, bringing the notch 138 into registration with the pin 136 at the upper end of the bell crank lever 134, whereupon the arm 140 swings downwardly to receive the pin 136 within said notch. The continued movement of the arm 140 swings the bell crank lever 134 counterclockwise, as seen in Fig. 1, thereby compressing the spring 130 and urging the gripper 76, 80 downwardly. As shown in Fig. 1, the compression spring 130 extends downwardly and forwardly from the bell crank lever 134 whereby the gripper 76, 80 is urged downwardly with a forward tendency sufficient to cause the actuation of the gripper to tend to hold the back of the shoe parts against the last.

Referring now to the mechanism for depressing the last forwardly of the grippers 30 in order to tension the upper heightwise thereof, a rotary cam 162 (Fig. 5) is pivoted to the forward end of the work support 26 for engagement with the forward end of a presser arm 164 formed integrally with the heel seat plate 56 and extending forwardly therefrom at the center of the last bottom laterally thereof. The under surface of the presser arm at its forward end is provided with gripping teeth 166 for engagement with the insole 168 tacked to the last bottom. In order to permit the presser arm 164 to swing toward and from the surface of the insole the combined presser arm and heel seat plate is provided at its rearward end with upstanding lugs 170 arranged to receive therebetween the downward extension 60 of the rearward end of the work support 26. The combined heel seat plate and presser arm is pivoted to said downward extension of the work support by a pin 174 carried by the upstanding lugs 170. A spring plunger 176 (Fig. 11) positioned rearwardly of the pivot pin 174 in a vertical bore extending upwardly from the under surface of the downward extension of the work support 26 urges the forward end of the presser arm 164 upwardly against the cam 162 and holds the presser arm above the surface of the insole when the cam 162 is in the position illustrated by Fig. 7. A further depression of the treadle 160 after the gripper 76, 80 has begun to pull downwardly upon the rearward end of the shoe parts

actuates mechanism for swinging the cam 162 counterclockwise, as seen in Fig. 7, to bring it into the position illustrated in Fig. 2. Said mechanism comprises a slide 178 arranged to 5 move in a guideway provided in the offset portion of the machine head. At its rearward end the slide 178 has a pin and slot connection with the upper end of the bell crank lever 142 and at its forward end the slide 178 has pivoted thereto 10 a roll 180 arranged to engage an arm 182 which projects upwardly with a rearward inclination from the cam 162 when the presser arm 164 is in its elevated position. A roll 184 pivoted to the forward end of the offset portion of the machine 15 head receives the upward thrust of the slide 178 incidental to the actuation of the cam 162.

As the cam 162 reaches the limit of its movement a tack driving mechanism is released to 20 drive a tack through the back of the shoe parts and into the rear end of the last at one side of the back seam of the upper. As illustrated, the tack driving mechanism comprises the tack driver 186, of usual construction (Fig. 1), mounted to slide in a tack driver guide 188 which, 25 in turn, is mounted to slide in a guideway formed in the extension 146 of the machine head (Fig. 12), the guide being retained within its guideway by the plate 144. The tack driver guide is moved from its retracted position, as shown in Fig. 1, 30 to its operative position, as shown in Fig. 2, by movement of the rocker arm 116 incidental to the movement of the work support 26 into operative position, the tack driver guide being provided with a groove 190 (Fig. 11) for the reception 35 of the rounded lower end of the rocker arm. In its forward position the forward end of the tack driver guide is spaced from the back of the upper, as shown in Fig. 2, in order to prevent any marking of the upper by the engagement of the 40 tack driver guide therewith. It will be seen that the forward position of the tack driver guide is accurately defined by the engagement of the latch pin 68 within the socket 62 provided in the work support. The tack to be driven into the 45 back of the heel is inserted manually into a tack receiving block 192 (Figs. 13 and 14) pivoted to the forward end of the tack driver guide 188 and yieldingly held upstanding by a torsion spring 194 wound upon a stud 196 (Fig. 14) projecting outwardly from the block 192 through an opening in 50 the wall of the tack driver guide, one end of said spring being connected to the wall of the tack driver guide and the other end to a collar 198 made fast to the stud 196. The upstanding position 55 of the tack receiving block 192 (Fig. 13) is determined by the engagement of a beveled surface 200 formed in the forward face of the tack receiving block with a beveled surface formed in the tack driver guide. At its lower end the tack receiving block is cut away to permit it to embrace a circular boss 202 (Fig. 14) in the tack driver guide about which boss the tack receiving block swings to bring it into alignment with the tack driver. There is provided in the tack receiving block 192 a tack hole 204 which is arranged to receive the tack driver 186 when the block has been swung into alignment with the tack driver, as shown in Fig. 2. A guard 206 (Fig. 13) projecting upwardly with a forward curvature from the tack driver guide 188 prevents the tack from being ejected from the tack receiving block by centrifugal force as the block is 60 swung into alignment with the tack driver. The tack receiving block 192 is swung into alignment 65 with the tack driver by the forward movement 70 75

of the tack driver guide to bring it into operative position. As shown in Fig. 1 the forward movement of the tack driver guide causes the forward face of the tack receiving block to engage a pin 208 projecting laterally from an arm 210 secured 5 to the front face of the machine head and swings the tack receiving block rearwardly to position its tack passage in alignment with the driver 186.

The tack driver 186 is released by connections from the treadle 160 to drive a tack through the back of the shoe parts and into the last at one side of the back seam. Preferably the extent of the stroke of the tack driver is such that the tack is driven only part way into the work in order to permit it to be removed readily therefrom. The connections from the treadle for releasing and actuating the tack driver comprise a link 212 pivoted at one end to a slide 214 within which one end of the tack driver is mounted, and pivoted at its opposite end to the upper end of an arm 216 pivoted coaxially with the arm 150 to the rearward extension of the machine head. The arm 150 is actuated by the treadle through connections hereinbefore described, and in the course of its downward movement it operates to energize the torsion spring 218 (Fig. 1) wound about the hubs of the arms 150 and 216 and having one end extended forwardly and arranged to engage beneath a pin 220 projecting laterally from the arm 150 and having its opposite end extended 30 rearwardly and arranged to engage the back face of a plate 222 formed integrally with, and at right angles to, the forward edge of the arm 216. A rocker arm or trigger 224 is pivoted to the machine head and arranged to engage the front and 35 upper edge faces of the plate 222 in order to hold the arm 216 in the position illustrated in Fig. 1 while the torsion spring 218 is being wound up and while the preliminary operations hereinbefore described are being performed upon the 40 shoe parts. The trigger 224 is released by the downward movement of the arm 150 through a link 226 which is pivoted at its upper end to the rearward end of the trigger 224 and which has at its lower end a pin and slot connection with 45 the forward end of the arm 150, the length of the slot in the link 226 being such that the release of the trigger 224 is timed to take effect when the work is prepared for the reception of the tack. The trigger 224 is yieldingly held in 50 operative position by a spring 228 connecting the forward end of the link to the machine head. The tack driver 186 is arrested by the engagement of the plate 222 with an abutment plate 229 extending outwardly from the machine head 55 (Fig. 15).

A further depression of the treadle, after the actuation of the tack driver, disengages the gripper blade 76 from the back of the upper and permits the gripper assembly to swing downwardly 60 until the gripper plate 80 has been completely disengaged from the last and shoe parts. The downward swinging movement of the gripper assembly is arrested by the engagement of a nut 234 at the upper end of the link 128 with the 65 top of the block 132 which is pivoted to the forward end of the bell crank lever 134 (Fig. 1) and held from downward movement thereby. The disengagement of the gripper blade 76 from the back of the upper is effected by connections 70 from the treadle actuated arm 150 comprising a link 236 having a pin and slot connection at its lower end with the forward end of the arm 150 (Fig. 15) and pivoted at its upper end to the rearward end of a rocker arm 238 (Fig. 1) which 75

in turn is pivoted to the plate 144 and connected at its forward end, by means of a link 240, to the rearward end of the lever 110 which actuates the segment 106 upon which the gripper blade 76 is supported. The actuation of the lever 110 by the connections above described causes it to swing in a counterclockwise direction, as seen in Fig. 1, thereby turning the segment 106 in a clockwise direction. As the treadle comes to the end of its depression the segment 106 and the gripper blade 76 have been brought into the position illustrated in Fig. 3 in which position the gripper blade has dropped away from the back of the upper sufficiently to disengage the gripper 76, 80 from the shoe parts. As the compression spring 130 which urges the gripper assembly downwardly is still under compression, the disengagement of the gripper 76, 80 from the shoe parts does not depend upon the action of gravity. Consequently, any tendency of the gripper plate 80 to be held between the shoe parts and the end of the last will not prevent the disengagement of the gripper plate from the work, the compression of the spring 130 being sufficient to overcome such resistance.

As the treadle comes to the end of its depression, a pin 230 projecting laterally from the slide 178 is brought into engagement with the bell crank lever 64, swinging said lever clockwise, as seen in Fig. 1, and disengaging the latch pin 60 from the socket 62 provided in the work support 26. The rocker arm 116 is then swung counterclockwise, as seen in Fig. 1, by a spring 232 connecting the lower end of the rocker arm to the plate 144 secured to the machine head to eject the work support 26 from the machine.

The depression of the treadle 160, from its beginning up to the point where the tack driver 186 is released, operates simultaneously with operations above described to press the last rearwardly and upwardly with relation to the shoe parts. As illustrated the mechanism for imparting these motions to the last comprises a sleeve 242 (Fig. 2) mounted in an oversized hole in a forward extension 244 of the machine column. At its lower end the sleeve 242 is pivoted to the upper end of a toggle arm 246 the lower end of which is pivoted to a toggle arm 248 which in turn is pivoted to the forward end of the treadle actuated rocker arm 154. The toggle is yieldingly held in straightened condition by an arm 250 which is urged rearwardly of the machine by a spring 252 connected at its forward end to the arm 250 and at its rearward end to the machine column. The swinging movement of arm 250 by the spring 252 is limited by the engagement of a downward extension 254 of the toggle arm 246 with the front edge face of the toggle arm 248 (Fig. 1). At its upper end the sleeve 242 has mounted therein a plunger 256 which is yieldingly supported upon a compression spring 258 which is supported at its lower end upon a seat formed in the sleeve 242. The plunger 256 is pivoted at its upper end to the forward end of a link 257 the rearward end of which is pivoted to the plate 144 (Fig. 1). The connection of the plunger 256 with said link operates to hold the plunger from turning movement, and a pin and slot connection 259 between the plunger and the sleeve 242 holds the sleeve from turning movement, thereby holding the toggle arm 246 in its proper position. A horizontal arm 260 is formed integrally with the plunger 256 at its upper end and arranged to extend forwardly of the machine. A bell crank lever 262

is pivoted to the rearward end of the arm 260 and a link 264 is pivoted to the forward end of the arm 260 and arranged in parallel relation to the upstanding arm of the bell crank lever 262. At its upper end the link 264 is pivoted to the forward end of a horizontal arm 266, said arm at its rearward end being pivoted to the upper end of the upstanding arm of the bell crank lever 262. It will thus be seen that the bell crank lever and the link 264 operate as a parallel motion mechanism for imparting a rearward movement to the arm 266. The bell crank lever is actuated to impart such movement to the arm 266 by connections from the sleeve 242 comprising an arm 268 clamped to the sleeve and extending forwardly therefrom, a link 270 pivoted at its upper end to the forward end of the horizontal arm of the bell crank lever 262 and arranged to slide through a vertical opening in the arm 268, and a compression spring 272. The compression spring 272, which is somewhat heavier than the compression spring 258, surrounds the link 270 and is held between the upper surface of the arm 268 and a shoulder 274 formed in the link 270. The upper surface of the arm 266 has gripping teeth formed therein for engagement with teeth formed in the under surface of a fixture 276 yieldingly retained within the last pin hole of the last. The fixture 276 comprises a horizontal plate having a last pin 278 projecting upwardly therefrom, said last pin having an open end slot extending downwardly from its upper end for the reception of a hairpin spring 280 (Fig. 16), the legs of which are bowed outwardly for engagement with the wall of the last pin hole. The spring 280 is supported at its upper end upon a cross pin 282 at the upper end of the last pin 278. At their lower ends the legs of the spring 280 are curved inwardly and cross each other at a point just above a cross pin 284 which is located just above the lower extremity of the slot provided in the last pin. At their lower ends each of the legs of the spring 280 has a reverse curvature formed therein to permit it partially to embrace the cross pin 284. The cross pin 284 thus limits the spreading of the legs of the spring 280 when the fixture 276 is removed from the last.

The first stage of the depression of the treadle 160 swings the rocker arm 154 clockwise, as seen in Fig. 1, lifting the sleeve 242 and the plunger 256 as a unit, thereby bringing the gripping teeth formed in the arm 266 into engagement with the teeth formed in the fixture 276. As the depression of the treadle continues the upward movement of the sleeve 242 continues but the plunger 256 remains at rest until the spring 258 has been compressed to such a point that it balances the pressure of the spring 272. During this interval the bell crank lever 262 is actuated by the upward movement of the sleeve 242 to urge the arm 266 rearwardly of the shoe parts and with it the last which has been inserted into the shoe parts, the last having been provided with a fixture 276. After the spring 258 has been compressed to the point where its compression is equal to that of the spring 272 the plunger 256 will be urged upwardly to press the last upwardly and urge the margin of the lining and the flange of the counter against the under surface of the heel seat plate 56. The rearward movement of the last by the bell crank lever 262 presses the upper extremity of the back of the shoe parts against a back stop 286. The part of the counter 61 adjacent to the heel seat is thus brought against the 75

rear end face of the last and caused to conform to the curvature thereof, and it is also brought against the rear edge face of the insole 168, provided the insole is properly located upon the last bottom with its rear edge face in alignment with the rear end face of the last. By pressing the counter firmly against the edge face of the insole the occurrence of a space between the rear edge face of the insole and the lining is prevented. The counter is held in this position by the gripping action of the last and the heel seat plate 56 upon the flange of the counter. At this point the tack driver 186 drives a tack through the back of the shoe parts and into the last in order to maintain the relative position of the last and the shoe parts at their heel ends. As illustrated, the back stop 286 (Fig. 2) consists of a horizontal arm pivoted at its rearward end to the head of a screw 288 projecting downwardly from the under surface of the extension 114 of the machine head. The back stop 286 is supported upon a pin 290 projecting laterally from the machine head. At its forward end the back stop is provided with a vertical slot to provide clearance for the curved pin 50 projecting rearwardly from the rear edge face of the heel seat plate 56. The shoe parts at their heel ends have a slight upward movement imparted thereto by the operation of the combined heel seat plate and presser arm 56 to press the last downwardly into the upper. The back stop 286 being pivoted at its rearward end, its forward end is free to move upwardly with the back of the shoe parts during the depression of the last. It is desirable, however, that the back stop be prevented from sliding upwardly upon the shoe parts and, accordingly, there is provided between the under surface of the extension 114 of the machine head and the upper surface of the back stop a compression spring 294, said spring being held in position by a stud 296 projecting downwardly from the extension 114.

A further depression of the treadle 160 after the actuation of the tack driver brings the toggle 246, 248 into the position illustrated in Fig. 2. In this position the pivot pin 298 connecting the arms of the toggle has engaged within a curved recess formed in the arm 250, and a further upward movement of the toggle thereafter causes the arm 250 to operate as a trigger to break the toggle and permit the sleeve 242, together with the plunger 256, to drop until it is arrested by the engagement of the arm 268 with the forward extension 244 of the machine column. As the plunger drops, the arm 266 disengages the under surface of the fixture 276 (Fig. 3).

The parts are reset for a repetition of the cycle of operations by the action of a treadle retracting spring 300, the upper end of which is connected to the machine column and the lower end of which is connected to the rocker arm 154 and arranged to rock said arm in a counter-clockwise direction, as seen in Fig. 3. The downward movement of the forward end of the rocker arm 154 straightens the toggle 246, 248 and the upward movement of the rearward end of the rocker arm swings the arm 150 in a clockwise direction, as seen in Fig. 3, bringing a lug 302 (Fig. 15) formed in the arm 150 into engagement with a lug 304 formed on the arm 216 and thereafter swinging the arms 150 and 216 as a unit to withdraw the tack driver 186. The tack driver guide 188 having been withdrawn to its initial position by the action of the rocker arm 116 in ejecting the work support 26 from the machine, the re-

traction of the tack driver permits the tack receiving block 192 to be returned to its initial position by the torsion spring 194 (Fig. 14). The upward movement of the rearward end of the rocker arm 154 also permits the link 235 to be returned to its initial position by the spring 306, the lower end of which is connected to said link and the upper end of which is pivoted to a pin 308 projecting laterally from the plate 144, the upward movement of said link by the spring 306 being limited by engagement of the upper edge face of the rocker arm 238 with the pin 308. The action of the spring 306 operates through the rocker arm 238, the link 240, and the lever 110 to swing the segment 106 in a counter-clockwise direction, bringing a cam face 310 (Fig. 9) formed in the forward edge face of the segment into engagement with a cam face 312 formed in the under surface of the tail piece 108 of the gripper blade 76 and returning the gripper blade to its initial position, as shown in Fig. 1. The upward movement of the rearward end of the rocker arm 154 permits the trigger 224 to be returned to its initial position, as shown in Fig. 1, by the spring 228. The upward movement of the arm 150 effected by the return movement of the rocker arm 154 moves the link 148 upwardly and swings the bell crank lever 142 in a clockwise direction, returning the slide 178 to its initial position, and causing the arm 140, which is pivoted to the bell crank lever 142, to swing the bell crank lever 134 clockwise thereof, as seen in Fig. 3, lifting the gripper 76, 80 together with the gripper assembly from their position, as shown in Fig. 3, to their initial position, as shown in Fig. 1. During the upward movement of the gripper assembly a V-shaped surface formed in an upward extension 314 of the arm 90 (Fig. 10) engages the stud 102, the arm 90 coming to rest with the angle of the V-shaped surface in engagement with the stud. A further movement of the bell crank lever 134, after the arm 90 has come to rest, swings the hollow link 92 upwardly, swinging the gripper plate 80 into its initial position, as seen in Fig. 11, and causing the cross pin 122 in the link 92 to engage the rear edge face of the hook 104, swinging the hook counter-clockwise, as seen in Fig. 10, and bringing it into engagement with the stud 102 in order to support the gripper assembly in its initial position. A continued movement of the bell crank lever 142 by the return of the rocker arm 154 to its initial position causes a pin 316 to engage beneath the arm 140 and disengage said arm from the pin 136 in the bell crank lever 134 (Fig. 1).

The work support 26 with the last and shoe parts held thereto may now be removed from the T-way 24 in the head of the machine and passed to the operator who is to perform the next succeeding operation upon the shoe parts. When, after the pulling over operation, and prior to the heel seat lasting operation, the work support is to be disengaged from the shoe parts, all that is necessary to effect such a removal of the work support is a manipulation of the gripper arms 38 in a clockwise direction, as seen in Fig. 6. The opening of the gripper jaws requires no considerable effort since their movement, from the start, is outward from the work as well as upward.

While the operation of the machine has been described in detail in connection with the description of the construction and arrangement of the various parts, the following summary of the operation of the machine may be useful. The operator first inserts a flanged counter between 75

an upper and lining to be assembled and shaped upon a last and brings the openings at the rearward ends of the margins of the parts into alinement. The operator then takes the work support 26 (which has been removed from the machine) and passes the curved hook 50 through the openings in the margins of the shoe parts and then slides the work support into the T-way 24 provided therefor in the machine head, bringing the parts into the position shown in Fig. 7 and causing the gripper 76, 80 to engage the back of the shoe parts. The margins of the shoe parts at opposite sides of their heel ends are then introduced between the jaws of the grippers 30. 15 The last 78 is then inserted into the upper, as shown in Fig. 8, and the heel end of the last is moved upwardly against the inner surface of the lining in order to remove from the lining any wrinkles that may have been formed therein by 20 the insertion of the counter between the upper and lining. The operator then steps on the treadle, thereby urging the gripper 76, 80 downwardly in order to tension the heel ends of the shoe parts heightwise thereof and to actuate the 25 combined heel seat plate and presser arm 56 to press the last into the upper in order to tension the upper heightwise thereof at opposite sides of its heel end. Simultaneously with the two foregoing operations, the sleeve 242 and plunger 30 256 and their associated mechanism operate to urge the last rearwardly and upwardly of the shoe parts, bringing the shoe parts against the front face of the back stop 286. The upward movement of the last causes the flange of the 35 counter to be engaged and held between the margin of the heel seat face of the last and the heel seat plate 56. A continued depression of the treadle actuates the tack driver 186 to drive a tack through the back of the shoe parts and 40 into the last at one side of the back seat in order to hold the parts in assembled condition upon the last. A still further depression of the treadle causes the retraction of the gripper blade 76 and a disengagement of the gripper 76, 80 from 45 the back of the shoe parts and then releases the latch pin 60 from the work support 26, thereby permitting the spring 232 to actuate the rocker arm 116 to eject the work support, together with the last and shoe parts, from the machine. 50 The retraction of the treadle 160 resets the parts of the machine for a repetition of the cycle of operations as above described.

Having fully described my invention, what I claim as new and desire to secure by Letters 55 Patent of the United States is:

1. That method of assembling and shaping shoe parts upon a last which comprises holding the extremity of the upper at the heel end of the shoe from movement heightwise of the last, tensioning the work heightwise of the last at opposite sides of its heel portion, holding the work so tensioned, and thereafter drawing the upper forwardly of the last.
2. That method of assembling and shaping shoe parts upon a last which comprises holding the extremity of the upper at the heel end of the shoe from movement heightwise of the last, gripping the margin of the work at opposite sides of its heel portion, imparting relative heightwise 60 movement to the last and upper at their heel portions in order to tension the upper heightwise of the last, holding the work so tensioned, and thereafter drawing the upper forwardly of the last.
3. That method of assembling and shaping shoe

parts upon a last which comprises holding the extremity of the upper at the heel end of the shoe from movement heightwise of the last, tensioning the work heightwise of the last at opposite sides of its heel portion and holding the work so tensioned while the upper is drawn forwardly of the last. 5

4. That method of assembling and shaping shoe parts upon a last which comprises holding the extremity of the upper at the heel end of the shoe from movement heightwise of the last, gripping the margin of the work at opposite sides of the heel portion thereof, imparting relative heightwise movement to the last and upper at their heel portions in order to tension the upper heightwise of the last, and holding the work so tensioned while the upper is drawn forwardly of the last. 10

5. That method of assembling and shaping shoe parts upon a last which comprises holding the heel end of the upper in the region of the back seam from movement heightwise thereof, tensioning the work heightwise of the last at opposite sides of its heel portion, and thereafter drawing the upper forwardly of the last. 20

6. That method of assembling and shaping shoe parts upon a last which comprises holding the heel end of the upper in the region of the back seam from movement heightwise thereof, gripping the margin of the work at opposite sides of the heel end thereof, imparting relative heightwise movement to the last and upper at their heel ends in order to tension the upper heightwise of the last, and holding the upper so tensioned while it is drawn forwardly of the last. 30

7. That method of assembling and shaping shoe parts upon a last which comprises engaging the shoe parts in the region of the upper extremity of the back seam, engaging the shoe parts in the region of the lower extremity of the back seam, 40 tensioning the work heightwise thereof in the region of the back seam, tensioning the work heightwise thereof at opposite sides of its heel portion, and holding the work so tensioned while the upper is drawn forwardly of the last. 45

8. That method for use in assembling and shaping shoe parts upon a last which consists in engaging the upper at opposite ends of the back seam and pulling the upper heightwise thereof.

9. That method of assembling and shaping shoe parts upon a last which comprises tensioning the heel end of the work heightwise thereof, and holding the margin of the work at opposite sides of the heel portion thereof from movement heightwise of the last while permitting movement of the work lengthwise of the last. 50

10. That method of assembling and shaping shoe parts upon a last which comprises tensioning the heel end of the work heightwise thereof, and positively holding the margin of the work at opposite sides of the heel portion thereof from movement heightwise of the last while permitting movement of the work lengthwise of the last. 60

11. That method of assembling and shaping shoe parts upon a last which comprises tensioning the heel end of the work heightwise thereof, and holding the margin of the work at opposite sides of the heel portion thereof from movement heightwise of the last while the last is 70 inserted into the upper and while the upper is drawn forwardly of the last.

12. That method of assembling and shaping shoe parts upon a last which comprises holding the margin of the work at opposite sides of the last 75

- heel portion thereof from movement heightwise of the last and pressing against the last bottom forwardly of the points at which the margin of the work is so held while holding the last from 5 movement heightwise thereof at its heel end.
13. That method of assembling and shaping shoe parts upon a last which comprises tensioning the heel end of the work heightwise thereof, holding the margin of the work at opposite sides 10 of the heel portion thereof, holding the margin of the work at its rearward extremity, pressing a last into the work, and driving a fastening through the work and into the last at the back of the heel.
14. That method of assembling and shaping a shoe upper, a flanged counter and a lining upon a last which comprises holding the work by the margin at the heel end thereof, inserting a last 15 into the work, and pressing the last heightwise thereof against the flange of the counter while the counter is held against movement heightwise of the last.
15. That method of assembling and shaping a shoe upper, a flanged counter and a lining upon a last which comprises holding the work by the margin at the heel end thereof, inserting a last into the work, urging the last rearwardly thereof, and pressing the last heightwise thereof against the flange of the counter while the counter is held against movement heightwise of the last.
16. That method of assembling and shaping a shoe upper, a flanged counter and a lining upon a last which comprises holding the work by the margin at the heel end thereof, inserting a last into the work, moving the rear end of the last heightwise thereof in order to smooth out the heel end of the lining, urging the last rearwardly thereof, and pressing the last heightwise thereof against the flange of the counter while the counter is held against movement heightwise of the last.
17. That method of assembling and shaping a shoe upper, a flanged counter and a lining upon a last which comprises holding the work by the margin at the forward ends of the counter, holding the work by the margin at the rearward end thereof, tensioning the heel end of the work heightwise thereof, inserting a last into the work, 45 moving the rear end of the last heightwise thereof in order to smooth out the heel end of the lining, urging the last rearwardly thereof, and pressing the last heightwise thereof against the flange of the counter while the counter is held against movement heightwise of the last.
18. That method of assembling and shaping a shoe upper, a flanged counter and a lining upon a last which comprises holding the work by the margin at the forward ends of the counter, holding the work by the margin at the rearward end thereof, inserting a last into the work, pressing the last rearwardly thereof, pressing the last heightwise thereof against the flange of the counter while the counter is held against movement heightwise of the last, and bringing the work against that portion of the back of the last adjacent to its heel-seat face in order to cause the counter to conform to the heightwise curvature of the rear end face of the last.
19. That method of assembling and shaping a shoe upper, a flanged counter and a lining upon a last which comprises holding the work by the margin at the forward ends of the counter, holding the work by the margin at the rear end thereof, inserting a last into the work,
- urging the last rearwardly thereof, holding the counter against movement heightwise thereof, and pressing the last heightwise thereof in order to flatten the margin of the lining between the marginal portion of the heel-seat face of the last and the flange of the counter and also, by the same movement, to position the counter heightwise of the last.
20. That method of assembling and shaping a shoe upper, a flanged counter and a lining upon a last which comprises holding the work by the margin at the forward ends of the counter, holding the work by the margin at the rear end thereof, bringing that portion of the heel end of the counter adjacent to the counter flange against that portion of the heel end of the last adjacent to its heel-seat face, and clamping the flange of the counter against the heel-seat face of the last in order to prevent the return of the counter to its initial position.
21. That method of assembling and shaping a shoe upper, a flanged counter, and a lining upon a last which comprises holding the work by the margin at points substantially adjacent to the forward ends of the counter, holding the work by the margin at the rear end thereof, bringing that portion of the heel end of the counter adjacent to the counter flange against that portion of the rear end face of the last adjacent to its heel-seat face, clamping the flange of the counter against the heel-seat face of the last in order to prevent the return of the counter to its initial position, and holding the flange of the counter pressed against the heel-seat face of the last while a fastening is driven through the heel end of the work and into the rear end face of the last.
22. That method of assembling a shoe upper, a counter and a lining upon a last which comprises marking the margins of the upper, counter and lining at their heel ends, bringing said marks into alignment, holding the work by the margin at the forward ends of the counter, holding the work by the margin at the heel end thereof, tensioning the heel end of the work heightwise thereof, and pressing a last into the work.
23. That method of assembling shoe parts upon a last which comprises forming an aperture in the margin of each of the parts at its heel end said apertures being so positioned that when they are brought into alignment the shoe parts, at that point, are properly arranged relatively to each other, holding the work by the margin at opposite sides of the heel portion thereof, holding the work by the margin at its rearward extremity, and inserting a last into the work.
24. That method for use in assembling an upper and a lining upon a last which comprises holding the extremity of the upper at its heel end from movement heightwise thereof, inserting a last into the upper, and moving the last heightwise of the upper in order to upwipe the lining.
25. That method for use in assembling an upper and a lining upon a last which comprises holding the extremity of the upper at its heel end from movement heightwise thereof, inserting a last into the upper, and moving the last rearwardly and heightwise of the upper in order to upwipe the lining.
26. That method for use in assembling shoe parts, including a lining, upon a last which comprises holding in fixed position the everlasting margin of the shoe parts in the region of the back seam, securing the shoe parts in the region of the opposite end of the back seam, inserting a last into the shoe, and moving the last rearwardly

and heightwise of the shoe in order to upwipe the lining.

27. That method for use in assembling an upper and a lining upon a last which comprises holding the extremity of the upper at its heel end from movement heightwise thereof, inserting a last into the upper, moving the last rearwardly of the upper, and moving the last heightwise of the upper to a predetermined limit in order to upwipe the lining.

28. That method for use in assembling an upper and a lining upon a last which comprises holding the upper at its heel end from movement heightwise thereof, arranging a last relatively to the upper with its heel end projecting therethrough, and rotating the last in a plane extending lengthwise of the last and heightwise thereof in order to upwipe the lining.

29. In a machine for assembling a shoe upper upon a last, work supporting means constructed and arranged to engage and grip the upper at opposite ends of the back seam.

30. In a machine for assembling a shoe upper upon a last, means constructed and arranged to engage the upper at opposite ends of the back seam in order to support the upper prior to the insertion of a last therein.

31. In a machine for assembling a shoe upper upon a last, upper engaging means for supporting the upper prior to the insertion of a last therein, said upper engaging means comprising a member constructed and arranged to engage the lasting allowance of the upper in the region of the back seam and to hold it in fixed position, and a member constructed and arranged to engage the upper at the opposite end of the back seam, said member being movable heightwise of the last.

32. In a machine for assembling a shoe upper upon a last, work supporting means comprising a member constructed and arranged to engage the lasting allowance of the upper in the region of the back seam and to hold it in fixed position, and a member constructed and arranged to engage the upper at the opposite end of the back seam, said member being movable heightwise of the last.

33. A machine for assembling a shoe upper upon its last having, in combination, work supporting means constructed and arranged to engage the margin at the heel end of the work, and means for tensioning the heel end of the work heightwise thereof.

34. A machine for assembling a shoe upper upon its last having, in combination, a member for engaging the lasting allowance of the upper in the region of the back seam, a gripper for engaging the upper in the region of the opposite end of the back seam, and means for imparting relative movement to the member and the gripper heightwise of the upper in order to tension the heel end of the upper.

35. A machine for assembling a shoe upper upon its last having, in combination, a member for engaging the lasting allowance of the upper in the region of the back seam, a gripper for engaging the upper in the region of the opposite end of the back seam, and means for moving the gripper heightwise of the upper relatively to the member in order to tension the heel end of the upper.

36. A machine for assembling a shoe upper upon its last having, in combination, a member for engaging the lasting allowance of the upper in the region of the back seam, a gripper for engaging the upper in the region of the opposite end

of the back seam, and means for yieldingly moving the gripper heightwise of the upper relatively to the member in order to tension the heel end of the upper.

37. A machine for assembling an upper upon its last having, in combination, operating instrumentalities and a support for the upper arranged to be removed from the machine with the upper and the last, said support being constructed and arranged to engage the margin of the upper at its heel end.

38. A machine for assembling an upper upon its last having, in combination, operating instrumentalities and a work support constructed and arranged to be removed from the machine with the last and upper, said support being provided with grippers for engaging the margin of the upper at opposite sides of its heel end and being provided also with means for supporting the margin of the upper at the back of the heel.

39. A machine for assembling an upper upon its last having, in combination, operating instrumentalities and a work support constructed and arranged to be removed from the machine with the last and upper, said support being provided with self-locking grippers for engaging the margin of the upper at opposite sides of its heel end.

40. A machine for assembling an upper upon its last having, in combination, operating instrumentalities and a work support constructed and arranged to be removed from the machine with the last and upper, said support being provided with self-locking grippers for engaging the margin of the upper at opposite sides of its heel end and being provided also with means for supporting the margin of the upper at the back of the heel.

41. In a machine for assembling an upper upon its last, a support for the upper comprising a pair of self-locking grippers constructed and arranged to engage the margin of the upper at opposite sides of its heel portion, and means for supporting the margin of the upper at the back of the heel.

42. In a machine for assembling an upper, a counter, and a lining upon a last, a work support constructed and arranged to be removed from the machine with the work, said work support comprising a member constructed and arranged to be slidably mounted in the machine frame, a pin upon which the rearward ends of the shoe parts are supported, and a pair of self-locking grippers arranged to engage the shoe parts at the forward ends of the counter.

43. In a machine for assembling an upper upon its last, a work support constructed and arranged to be removed from the machine with the last and upper, said support being provided with grippers for engaging the margin of the upper, said grippers being so constructed that a pull on the work tending to withdraw the work from the grippers urges the gripping surfaces toward each other, thereby increasing the gripping action.

44. In a machine for operating upon shoe parts, a gripper having a fixed jaw and a movable jaw, said movable jaw being pivoted at a point which is spaced from the gripping surfaces of said jaws, heightwise of the work, in the direction of a pull on the work tending to withdraw the work from the gripper.

45. In a machine for assembling an upper upon its last, a gripper arranged to engage the margin of the upper, said gripper comprising a stationary gripping member and a movable gripping member arranged to be moved away from the station-

ary member by the introduction of the work therebetween and arranged to be moved toward the stationary member by a pull on the work tending to withdraw the work from the gripper.

- 5 46. In a machine for assembling an upper upon its last, a gripper arranged to engage the margin of the upper, said gripper comprising a U-shaped member one arm of which is longer than the other, the shorter arm having work gripping teeth formed on its inner face, and a movable member mounted at the end of the longer arm of the U-shaped member for swinging movement in the plane of said U-shaped member, said movable member being provided with work gripping teeth arranged to face the work gripping teeth formed in the U-shaped member.

- 10 47. In a machine for assembling an upper upon its last, a gripper arranged to engage the margin of the upper, said gripper comprising a U-shaped member one arm of which is longer than the other, the short arm having work gripping teeth formed on its inner face, and a movable member mounted at the end of the longer arm of the U-shaped member for swinging movement in the plane of said U-shaped member, said movable member being provided with work gripping teeth arranged to face the work gripping teeth formed in the U-shaped member, said movable member having a tail piece formed integrally therewith whereby said movable member may conveniently be manipulated to open the gripper in order to release the upper therefrom.

- 15 48. In a machine for assembling an upper upon its last, a work support comprising a slide constructed and arranged to be removed from the machine with the last and upper, and a plurality of grippers for engaging the margin of the upper, each of said grippers comprising a U-shaped member arranged for swinging movement relatively to the slide, said U-shaped member having one arm which is longer than the other, the short arm having work gripping teeth formed on its inner face, and a movable member mounted at the end of the longer arm of the U-shaped member for swinging movement in the plane of said member, said movable member being provided with work gripping teeth arranged to face the work gripping teeth formed in the U-shaped member.

- 20 49. In a machine for assembling an upper upon its last, a work support constructed and arranged to be removed from the machine with the last and upper, and a plurality of upper engaging grippers carried by the support.

- 25 50. In a machine for assembling and shaping shoe parts upon a last, a work support constructed and arranged to be removed from the machine with the work, said work support comprising grippers arranged to engage the margin of the work at opposite sides of the heel portion thereof, a supporting member for engaging the margin of the work at the back of the heel, and a presser for pressing against the last bottom forwardly of the grippers.

- 30 51. In a machine for assembling and shaping shoe parts upon a last, a work support constructed and arranged to be removed from the machine with the work, said work support comprising grippers arranged to engage the margin of the work at opposite sides of the heel portion thereof, a supporting member for engaging the margin of the work at the back of the heel, a presser for pressing against the last bottom forwardly of the grippers, and a cam for actuating the presser.

- 35 52. In a machine for assembling and shaping

shoe parts upon a last, a work support constructed and arranged to be removed from the machine with the work, said work support comprising grippers arranged to engage the margin of the work at opposite sides of the heel portion thereof, a supporting member for engaging the margin of the work at the back of the heel, and a presser for pressing against the last bottom forwardly of the grippers, said presser being provided with means for holding the last from forward movement relatively to the shoe parts.

40 53. In a machine for assembling and shaping shoe parts upon a last, a work support constructed and arranged to be removed from the machine with the work, said work support comprising self-locking grippers arranged to engage the margin of the work at opposite sides of the heel portion thereof, a supporting pin for engaging the margin of the work at the back of the heel, and a presser for pressing against the last bottom forwardly of the grippers, said presser being provided with teeth for holding the last from forward movement relatively to the shoe parts.

45 54. In a machine for assembling and shaping an upper, a flanged counter and a lining upon a last, a work support constructed and arranged to be removed from the machine with the work, said work support comprising grippers for engaging the margin of the work at opposite sides of the heel end thereof, a work supporting member for engaging the margin of the work at the back of the heel, a heel-seat plate having the general outline of the periphery of the heel-seat face of the last, a presser for pressing against the last bottom forwardly of the grippers, and means for actuating the presser.

50 55. In a machine for assembling and shaping a shoe upper, a flanged counter, and a lining upon a last, a clamp for holding the shoe parts to the last constructed and arranged to be removed from the machine with the last and the shoe parts, said clamp comprising a pair of self-locking grippers for engaging the margins of the shoe parts at the forward ends of the counter, a pin for engaging the margin of the shoe parts at the back of their heel ends, a heel-seat plate arranged to engage the flange of the counter, a presser formed integrally with the heel-seat plate and arranged to extend forwardly of the self-locking grippers, and means for urging said presser against the last bottom in order to tension the shoe parts heightwise of the last.

55 56. In a machine for assembling shoe parts upon a last, a support for the shoe parts constructed and arranged to be removed from the machine with the work, a machine head provided with a guideway for the work support, and means for ejecting the work support from the machine.

60 57. In a machine for assembling shoe parts upon a last, a support for the shoe parts constructed and arranged to be removed from the machine with the work, a machine head provided with a guideway for the work support, means for holding the work support in operative position, and means for ejecting the work support from the machine.

65 58. In a machine for assembling shoe parts upon a last, a support for the shoe parts constructed and arranged to be removed from the machine with the work, a machine head provided with a guideway for the work support, a latch for determining the operative position of the work support and maintaining the work

- support in operative position, and means for ejecting the work support from the machine.
59. A machine for assembling and shaping an upper upon its last having, in combination, 5 means for holding the upper by its margin, and means for urging the last lengthwise and heightwise of the upper.
60. A machine for assembling and shaping a shoe upper, a flanged counter and a lining upon 10 a last having, in combination, a support for the margin at the heel end of the shoe parts, means for pressing the last against the flange of the counter, and means arranged to oppose the pressure of the last against the flange of 15 the counter.
61. A machine for assembling and shaping a shoe upper, a flanged counter and a lining upon a last having, in combination, a support for the margin at the heel end of the shoe parts, means 20 for pressing the last against the flange of the counter, and a stop arranged to oppose the pressure of the last against the flange of the counter.
62. A machine for assembling an upper upon a last having, in combination, means for holding the upper at its heel end from movement heightwise thereof, means for moving the heel end of the last heightwise of the upper, and a stop for arresting said movement of the last. 25
63. A machine for assembling an upper upon a last having, in combination, means for holding the upper at its heel end from movement heightwise thereof, means for moving the heel end of the last heightwise of the upper, and a stop movable heightwise of the upper for ar- 30
- 35 resting said movement of the last.
64. A machine for assembling and shaping a shoe upper, a flanged counter and a lining upon a last having, in combination, a support for the margin at the heel end of the shoe part, means 40 for pressing the last against the flange of the counter, and a stop having the outline of the heel-seat face of the last and arranged to oppose the pressure of the last against the flange of the counter.
- 45 65. A machine for assembling and shaping a shoe upper, a flanged counter and a lining upon a last having, in combination, a support for the margin at the heel end of the shoe parts, means for pressing the last against the flange of the counter, a stop arranged to oppose the pressure of the last against the flange of the counter, and means for urging the last rearwardly of the shoe parts. 50
66. A machine for assembling and shaping a shoe upper, a flanged counter and a lining upon a last having, in combination, a support for the margin of the heel end of the shoe parts, means 55 for pressing the last against the flange of the counter, and a stop constructed and arranged to engage the flange of the counter in order to oppose the pressure of the last against said flange.
67. In a machine for assembling an upper upon its last, a gripper for engaging the upper in the region of the end of the back seam opposite 60 the lasting allowance, and means for pressing the last against the flange of the counter while the upper is held by the gripper.
68. In a machine for assembling an upper upon its last, a gripper for engaging the upper in the region of the end of the back seam opposite 65 the lasting allowance, a stop constructed and arranged to engage the flange of the counter, and means for pressing the last against the flange of the counter and thereby pressing the 70 counter against said stop.
69. A machine for assembling and shaping a shoe upper, a flanged counter and a lining upon a last having, in combination, means for urging the last rearwardly of the shoe parts, and means arranged to be engaged by that portion of the heel end of the upper that is adjacent to the heel-seat in order to arrest the rearward movement of the last and also to cause the counter to conform to the heightwise curvature of the rear end face of the last. 75
70. A machine for assembling and shaping a shoe upper, a flanged counter and a lining upon a last having, in combination, means for urging the last rearwardly of the shoe parts, a back stop arranged to be engaged by that portion of the heel end of the upper that is adjacent to the heel-seat in order to arrest the rearward movement of the last and also to cause the counter to conform to the heightwise curvature of the rear end face of the last, and means for clamping the flange of the counter in order to hold the counter in said position. 10
71. A machine for assembling and shaping an upper upon its last having, in combination, means for holding the upper by its margin, means for 15 pressing the last into the upper, and means for urging the last rearwardly and upwardly. 20
72. A machine for assembling and shaping an upper upon its last having, in combination, a work support for holding the upper by its margin, a presser for pressing the last into the upper, and a presser for urging the last rearwardly and upwardly. 30
73. A machine for assembling and shaping an upper upon its last having, in combination, a portable work support for holding the upper by its margin, a presser for pressing the last into the upper, and a presser for urging the last rearwardly and upwardly. 35
74. A machine for assembling and shaping an upper upon its last having, in combination, means for holding the upper by its margin, means for pressing the last into the upper comprising a fixture constructed and arranged to be retained within the last pin hole provided in the last, a member arranged to engage said fixture, and means for urging said member rearwardly and upwardly of the last. 40
75. A machine for assembling and shaping an upper upon its last having, in combination, means for holding an upper by its margin, means for pressing the last into the upper comprising a fixture constructed and arranged to be retained within the last pin hole provided in the last, a member arranged for engagement with 50 said fixture, interengaging gripping surfaces formed in said fixture and said member, and means for urging said member rearwardly and upwardly of the last. 55
76. A machine for assembling and shaping an upper upon its last having, in combination, means for holding an upper by its margin, means for pressing the last into the upper comprising a fixture constructed and arranged to be yieldingly retained within the last pin hole provided in the last, a member arranged for engagement with said fixture, interengaging gripping surfaces formed in said fixture and said member, and a presser for urging said member rearwardly of the last and then simultaneously upwardly and 60 rearwardly of the last. 65
77. A machine for assembling and shaping an upper upon its last having, in combination, means for holding the upper by its margin, means for pressing the last into the upper com- 75

prising a fixture constructed and arranged to be retained within the last pin hole provided in the last, a member arranged for engagement with said fixture, interengaging gripping surfaces 5 formed in said fixture and said member, a presser for urging said member rearwardly and upwardly of the last, means for actuating said presser, a toggle connecting said actuating means and said presser, and means for automatically breaking said toggle in order to disengage said member from the fixture.

78. A machine for assembling and shaping an upper upon its last having, in combination, 15 means for holding the upper by its margin, means for pressing the last into the upper comprising a fixture constructed and arranged to be retained within the last pin hole provided in the last, a member arranged for engagement with said fixture, interengaging gripping surfaces 20 formed in said fixture and said member, a presser for urging said member rearwardly and upwardly of the last, means for actuating said presser, a toggle connecting said actuating means and said presser, a trigger for automatically breaking said 25 toggle in order to disengage the presser from the fixture, and parallel motion mechanism on which said member is supported.

79. A machine for assembling and shaping an upper upon its last having, in combination, 30 means for supporting the upper by its margin, means for pressing the last into the upper comprising a fixture yieldingly retained within the last pin hole of the last, a member arranged to engage said fixture and a presser for pressing 35 said member rearwardly and upwardly of the last, said presser comprising a vertically movable sleeve arranged heightwise of the last, a plunger yieldingly supported therein, parallel motion mechanism including a bell crank lever connecting the plunger and the fixture actuating member, and connections between the sleeve and the bell crank lever.

80. A machine for assembling and shaping an upper upon its last having, in combination, 45 means for supporting the upper by its margin, means for pressing the last into the upper comprising a fixture yieldingly retained within the last pin hole of the last, a member arranged to engage said fixture and a presser for pressing 50 said member upwardly and rearwardly of the last, said presser comprising a vertically movable sleeve arranged heightwise of the last, a compression spring contained within said sleeve and seated at its lower end, a plunger slidably mounted in said sleeve and supported by said spring, a bell crank lever carried by said plunger and pivoted at the end of its vertical arm to the fixture actuating member, and connections between the horizontal arm of the bell crank lever and the vertically movable sleeve including a compression spring heavier than the plunger supporting spring.

81. A machine for assembling an upper upon its last having, in combination, an upper supporting member arranged to engage the margin of the upper at its heel end, and means constructed and arranged to engage the upper in the crease of the back seam in order to locate the back seam in a vertical plane extending lengthwise of the upper.

82. A machine for assembling an upper upon its last having, in combination, an upper supporting member arranged to engage the margin of the upper at its heel end, and a clamping member constructed and arranged to engage the

upper in the crease of the back seam in order to locate the back seam in a vertical plane extending lengthwise of the upper.

83. A machine for assembling and shaping an upper upon its last having, in combination, a support constructed and arranged to hold the heel end of the upper by its margin, a machine head provided with a guideway for said support, a clamp constructed and arranged to engage the heel end of the upper, and means actuated by 10 sliding the support into operative position in its guideway for causing said clamp to engage the upper.

84. A machine for assembling and shaping an upper upon its last having, in combination, a 15 support constructed and arranged to hold the heel end of the upper by its margin, means for tensioning the upper at its heel end heightwise of the last including a clamp which consists of a member arranged to engage the upper in the 20 crease of the back seam, and an opposing member arranged to be actuated by a movement imparted to the work support to engage the inner surface of the heel end of the upper.

85. A machine for assembling and shaping an upper upon its last having, in combination, a support constructed and arranged to hold the heel end of the upper by its margin, means for tensioning the upper at its heel end heightwise of the last including a clamp which consists of 30 a member arranged to engage the upper in the crease of the back seam, an opposing member arranged to be actuated by a movement imparted to the work support to engage the inner surface of the heel end of the upper, and a compression 35 spring arranged to hold said opposing member in its clamped position.

86. A machine for assembling and shaping an upper upon its last having, in combination, a support constructed and arranged to hold the 40 heel end of the upper by its margin, means for tensioning the upper at its heel end heightwise of the last comprising a clamp which consists of a member arranged to engage the upper in the crease of the back seam, an opposing member 45 arranged to be actuated by a movement imparted to the work support to engage the inner surface of the heel end of the upper, and means for actuating said clamp to tension the heel end of the upper heightwise thereof.

87. A machine for assembling and shaping an upper upon its last having, in combination, a support constructed and arranged to hold the heel end of the upper by its margin, means for tensioning the upper at its heel end heightwise of 55 the last comprising a clamp which consists of a member arranged to engage the upper in the crease of the back seam, and an opposing member arranged to be actuated by a movement imparted to the work support to engage the inner 60 surface of the heel end of the upper, a driver for inserting a fastening through the upper and into the last at one side of the back seam, and means for releasing the clamp from the upper.

88. In a machine for assembling and shaping 65 an upper upon its last, a support for the upper arranged to engage the upper margin at its rearward end, a clamp arranged to engage the heel end of the upper at that end of the back seam opposite to said support, said clamp comprising 70 a clamping blade arranged to engage the upper in the crease of the back seam, means for supporting said blade in clamping position, a clamping member arranged to engage the inner surface of the upper, a treadle, and connections from 75

the treadle for releasing said blade supporting means in order to permit disengagement of the clamp from the upper.

89. In a machine for assembling and shaping an upper upon its last, a support for the upper constructed and arranged to engage the upper margin at its rearward end, a clamp arranged to engage the heel end of the upper at that end of the back seam opposite to said support, said clamp comprising a clamping blade arranged to engage the upper in the crease of the back seam, a support for retaining said blade in clamping position, a clamping plate arranged to engage the inner surface of the upper, and means for releasing said blade supporting means in order to permit disengagement of the clamp from the upper.
90. In a machine for assembling shoe parts upon a last, a work support constructed and arranged to hold the upper by its margin, a machine head provided with a guideway for the reception of the work support, a tack driver for driving a tack through the upper and into the rear end face of the last, a tack driver guide, and means actuated by sliding the work support into operative position in its guideway to bring the guide into operative position.

91. In a machine for assembling shoe parts upon a last, a work support constructed and arranged to hold the upper by its margin, a machine head provided with a guideway for the reception of the work support, a tack driver for driving a tack through the upper and into the rear end face of the last, a tack driver guide, and lever and link connections between the work support and the guide whereby the sliding movement imparted to the work support to bring it into operative position brings the driver guide into operative position.

92. In a machine for assembling shoe parts upon a last, a work support constructed and arranged to hold the upper by its margin, a machine head provided with a guideway for the reception of the work support, a tack driver for driving a tack through the rear end of the upper and into the rear end face of the last, a tack driver guide, a normally upstanding tack receiving block carried by the guide, and means actuated by a sliding movement imparted to the work support to bring the guide into operative position and to swing the tack receiving block in order to bring the tack into position to be driven.

93. In a machine for assembling an upper upon its last, means for driving a tack substantially horizontally through the upper and into the last at one side of the back seam comprising a tack driver, a guide therefor, a tack receiving block carried by the guide and normally maintained upstanding, and means for actuating the tack receiving block in order to bring the tack into alignment with the tack driver.

94. In a machine for assembling an upper upon its last, means for supporting the rearward end of the upper by its margin, a gripper for engaging the upper in the crease of the back seam, and means for imparting relative movement to the support and the gripper heightwise of the upper in order to tension the heel end of the upper.

95. In a machine for assembling an upper upon its last, a support for engaging the lasting allowance of the upper, a gripper for engaging the upper in the region of the end of the back seam opposite the lasting allowance, and means for imparting relative movement to the support and

the gripper heightwise of the upper in order to tension the heel end of the upper.

96. In a machine for assembling an upper upon its last, means for holding the rearward end of the upper by its margin, a gripper for engaging the rearward end of the upper within the back seam, and means for depressing the gripper in order to tension the heel end of the upper.

97. In a machine for assembling an upper upon its last, means for holding the rearward end of the upper by its margin, a gripper for engaging the rearward end of the upper within the back seam, a support for the gripper, and treadle actuated means for imparting a swinging movement to said support whereby the gripper is depressed in order to tension the heel end of the upper heightwise thereof.

98. In a machine for assembling an upper upon its last, means for holding the rearward end of the upper by its margin, a gripper for engaging the rearward end of the upper in the crease of the back seam, an arm for carrying the gripper, a spring carried by the arm, and means for energizing said spring to cause the gripper to pull on the heel end of the upper to tension it heightwise thereof.

99. In a machine for assembling an upper upon its last, means for holding the rearward end of the upper by its margin, a gripper for engaging the rearward end of the upper within the back seam, an arm for carrying the gripper arranged for movement both lengthwise and heightwise of the last, a spring carried by said arm, and means for energizing said spring whereby the gripper pulls on the heel end of the upper to tension it heightwise thereof.

100. In a machine for assembling an upper upon its last, means for holding the rearward end of the upper by its margin, a gripper for engaging the rearward end of the upper at the back seam, an arm for carrying the gripper, a spring carried by the arm, means for energizing said spring whereby the gripper pulls on the heel end of the upper to tension it heightwise thereof, means for releasing the gripper, means for moving the upper from operative position, means for returning the gripper to its initial position, and automatically actuated means for retaining the gripper in said position.

101. In a machine for assembling an upper upon its last, means for holding the rearward end of the upper by its margin, a gripper for engaging the rearward end of the upper at the back seam, an arm for carrying the gripper, a spring carried by the arm, means for energizing said spring in order to actuate said arm to tension the heel end of the upper heightwise thereof, a treadle, lever and link connections between the treadle and said arm for returning the gripper to its initial position, a retaining member for holding the gripper in its initial position, and means actuated by the return movement of the gripper to bring said retaining member into operative position.

102. In a machine for assembling an upper upon its last, means for holding the rearward end of the upper by its margin, and means co-operating with said supporting means to tension the upper at its heel end comprising a gripper consisting of a member constructed and arranged to engage the upper within the crease of the back seam and a curved plate arranged to engage the inner surface of the upper, a treadle, connections from the treadle for releasing the gripper, treadle actuated means for moving the upper from operative position, lever and link connections from

the treadle for returning the gripper to its initial position, a retaining member for holding the gripper in its initial position, means actuated by the return movement of the gripper to bring the retaining member into operative position, and means actuated by the return movement of the gripper to reset the curved gripper plate in its initial position.

103. In a machine for assembling an upper upon its last, means for holding the rearward end of the upper by its margin, a gripper co-operating with said holding means to tension the upper at its heel end comprising a pair of jaws consisting of a blade-like jaw constructed and arranged to engage the upper in the crease of the back seam and a curved plate-like jaw arranged to engage the inner surface of the upper, a carrier for the gripper, a treadle, connections from the treadle for releasing the blade, lever and link connections between the treadle and the carrier for returning the carrier to its initial position, a retaining member for holding the carrier in its initial position, means actuated by the return movement of the carrier to bring the retaining member into operative position, means actuated by the treadle to return the curved plate-like jaw to its inoperative position, and mechanism arranged to be actuated during the retraction of the treadle to return the blade-like jaw to its operative position.

30 104. In a machine for assembling an upper upon its last, means for holding the rearward end of the upper by its margin, a gripper for engaging the rearward end of the upper at the back seam, an arm for carrying the gripper, a treadle, lever and link connections between the treadle and said arm for returning the gripper to its initial position, and means for breaking said connections.

105. In a machine for assembling a shoe upper upon its last, means for supporting the upper by the lasting allowance, a gripper constructed and arranged to engage the upper in the region of the end of the back seam opposite the lasting allowance, means for moving the gripper heightwise of the upper in order to tension the heel end of the upper, and means for automatically disengaging the gripper from the upper.

50 106. In a machine for assembling a shoe upper upon its last, a support for the upper arranged to engage the lasting allowance at the heel end of the upper, a gripper constructed and arranged to engage the upper in the region of the end of the back seam opposite the lasting allowance, means for moving the gripper heightwise of the upper in order to tension the heel end of the upper, and means for automatically disengaging the gripper from the upper.

107. In a machine for assembling a shoe upper upon its last, means for supporting the upper by the lasting allowance, a gripper constructed and arranged to engage the upper in the region of the end of the back seam opposite the lasting allowance, means for moving the gripper heightwise of the upper in order to tension the heel end of the upper, means for automatically opening the gripper, and means for moving the gripper out of contact with the upper.

10 108. In a machine for assembling a shoe upper upon its last, means for supporting the upper by the lasting allowance, a gripper constructed and arranged to engage the upper in the region of the end of the back seam opposite the lasting allowance, means for moving the gripper heightwise of the upper in order to tension the heel end of the upper, means for moving the last heightwise of the upper, and means for automatically disengaging the gripper from the upper.

15 109. In a machine for assembling a shoe upper upon its last, means for supporting the upper by the lasting allowance, a gripper constructed and arranged to engage the upper in the region of the end of the back seam opposite the lasting allowance, means for moving the gripper heightwise of the upper in order to tension the heel end of the upper, means for moving the last heightwise of the upper, a stop for limiting the heightwise movement of the last, and means for automatically disengaging the gripper from the upper.

20 110. In a machine for assembling a shoe upper upon its last, means for supporting the upper by the lasting allowance, a gripper constructed and arranged to engage the upper in the region of the end of the back seam opposite the lasting allowance, means for moving the gripper heightwise of the upper in order to tension the heel end of the upper, means for moving the last rearwardly and heightwise of the upper, and means for automatically disengaging the gripper from the upper.

25 111. In a machine for assembling a shoe upper upon its last, means for supporting the upper by the lasting allowance, a gripper constructed and arranged to engage the upper in the region of the end of the back seam opposite the lasting allowance, means for moving the gripper heightwise of the upper in order to tension the heel end of the upper, means for moving the last rearwardly and heightwise of the upper, a stop for limiting the heightwise movement of the upper, a stop for limiting the rearward movement of the upper, and means for automatically disengaging the gripper from the upper.

December 15, 1936.

ROBERT H. LAWSON.

It is hereby certified that error appears in the printed specification of the above numbered patent requiring correction as follows: Page 8, first column, line 40, for the word "seat" read seam; page 14, first column, lines 63-64, claim 94, strike out the words "the rearward end of" and insert the same before "the" first occurrence, line 65, same claim; and that the said Letters Patent should be read with these corrections therein that the same may conform to the record of the case in the Patent Office.

Signed and sealed this 27th day of July, A. D. 1937.

(Seal)

Henry Van Arsdale

Acting Commissioner of Patents.
